HARLAN P. BOWMAN, OF GREENSBORO, NORTH CAROLINA.

ATTACHMENT FOR DRINKING-CUPS.

1,280,942.

Specification of Letters Patent.

Patented Oct. 8, 1918.

Application filed April 28, 1917. Serial No. 165,209.

To all whom it may concern:

Be it known that I, GROVER C. APPLE, a citizen of the United States, residing at Greensboro, in the county of Guilford and 5 State of North Carolina, have invented new and useful Improvements in Attachments for Drinking-Cups, of which the following is a specification.

This invention comprehends the provision 10 of an attachment for cups, drinking glasses or the like, and is primarily designed for use by infants, young children, and invalids confined to their bed, although it is susceptible for use by others. The invention 15 has in view the provision of means to prevent spilling of the contents of the cup or glass while in use, upon the clothes of the user, table cloth or bed clothing.

The nature and advantages of the invention 20 will be better understood from the following detail description when considered in connection with the accompanying drawing, the invention residing in the construction, combination and arrangement of parts 25 as claimed.

In the drawing forming part of this specification like numerals of reference indicate similar parts in the several views, and wherein:—

30 Figure 1 is a perspective view showing the attachment in position upon a drinking vessel.

Fig. 2 is a top plan view.

Fig. 3 is a vertical sectional view.

35 Fig. 4 is a sectional view taken on line 4—4 of Fig. 1.

The attachment forming the subject matter of my invention is in the nature of a flanged cap 10 constituting a cover for a 40 drinking vessel such as a cup, glass or the like. The cap is adapted to be fitted upon the mouth of the vessel herein indicated at 11, with the flange 12 preferably fitted within the vessel. The cap has a diameter 45 slightly greater than the mouth of the drinking vessel 11 so that the edge of the cap will protrude a slight distance beyond the body of the vessel to facilitate handling of the 50 cap, when associating the cap with the vessel or removing the same therefrom. The cap is provided with an outlet opening 13, while surrounding said opening and rising from the cap is a hollow boss 14. The boss 55 may vary in dimensions consistent with the size of the cap, and terminates to provide

an inwardly directed flange 15 constituting a valve seat and provided with a restricted centrally disposed opening 16. The boss is preferably threaded to removably accommodate the enlarged threaded portion 17 of 60 a nipple indicated generally at 18. The nipple is reduced or contracted at its upper extremity to provide a relatively narrow elongated mouth piece 19, the latter being perforated as at 20. Aside from the perforations which are very small, it is obvious that the mouth piece is otherwise closed to prevent insects or the like gaining access thereto. The mouth piece is also formed with rounded edges so as to prevent injury to the 70 mouth of the user.

Normally seated upon the flange 15 constituting the valve seat, is a disk valve 21, while interposed between the valve and the mouth piece is a spring 22 constructed from 75 very light material and very sensitive, so as to readily and easily yield to permit opening of the valve when subjected to a slight suction, when the user endeavors to draw the contents from the cup or drinking vessel 80 into the mouth. While the spring is extremely sensitive for this purpose, it has sufficient tension to maintain the valve against its seat in a position to close the opening 16, so that casual spilling of the 85 contents from the cup during the use of the latter, is positively prohibited. The peripheral edge of the valve is split at spaced intervals to provide a tongue 23 which is adapted to be bent over one of the adjacent 90 convolutions of the spring with a view of maintaining the spring and valve fixed relatively. Any number of these tongues may be provided, and when these tongues are bent into engagement with the spring as 95 stated the valve is provided with ports 24 which permit the fluid drawn from the vessel to pass from beneath the valve into the mouth, when the valve is moved to an open position. It will now be observed that the 100 valve 21 and the spring 22 are disposed within the nipple 18, and as the latter is detachably associated with the boss 14 access may be readily had to the several parts, when it is desired to clean the same, or for 105 any other purpose, by merely separating the nipple from the boss 14.

The cap 10 may if desired be provided with a vent opening 25 for the admittance of air to facilitate the flow of the contents, 110

and this opening is normally closed by a flat resilient element 26, secured to the underside of the cap at one end, and having its free extremity underlying the opening. This element 26 is in the nature of a valve which when subjected to a slight suction is moved downwardly away from the opening 25 for the admittance of air into the vessel for the purpose above mentioned. While the vent 10 opening 25 is essential, the resilient element 26 may be eliminated. Again however if desired the resilient element or valve 26 may be used solely, in which instance the valve 21 and spring 22 are eliminated. If the 15 resilient element or valve 26 is used in preference to the valve 21 and spring 22, the boss 14 may be terminated to provide a perforated mouth piece, in which instance the nipple 18 can also be disposed of. It might 20 here be stated that the attachment in its entirety can be constructed from any suitable material and of any desired cross sectional configuration without departing from the spirit of the invention.

25 While it is believed that from the foregoing description the nature and advantages of the invention will be apparent, I desire to have it understood that what is shown and described is not considered restrictive, 30 and that such changes may be resorted to when desired as fall within the scope of what is claimed.

What is claimed is:—

35 1. A cup attachment embodying a closure therefor having a vent opening, a hollow boss rising from the closure and communicating with the cup, a valve seat, a spring 40 pressed disk valve normally engaging said seat for controlling the communication between the cup and said boss, a nipple detachably secured to the boss and formed to provide a reduced perforated mouth piece, and said disk being notched at spaced intervals to provide ports for the outflow of the 45 contents from the cup to the nipple.

2. A cup attachment embodying a closure therefor, having a vent opening, a hollow

boss rising from the closure and communicating with the cup, a valve seat, a nipple 50 detachably secured to the boss and formed with a reduced perforated mouth piece, a disk valve movable within the nipple and normally engaging said seat for controlling communication between the boss and said cup, a spring disposed within the nipple for holding said valve normally seated, said valve being split at spaced intervals to provide a tongue adapted to be bent into engagement with the spring to hold said valve and spring fixed relatively, and said tongue 55 when bent into engagement with the spring provides a port in said valve for the outflow of the contents from the cup to the nipple when the valve is in opened position.

3. A cup attachment embodying a closure 60 therefor having a vent opening, a leaf spring secured to the under side of the cover and having its free extremity normally overlying said opening, a hollow extension rising from the closure and communicating with the cup, 65 a perforated mouth piece on said extension, and said spring being adapted to be moved away from the said opening by suction.

4. A cup attachment embodying a closure 70 therefor having a vent opening, a hollow boss rising from the closure and communicating with said cup, a perforated mouth piece associated with the extension, and a spring pressed valve arranged within the mouth piece and controlling the communication 75 between the latter and said cup.

5. A cup attachment embodying a closure 80 therefor having a vent opening, a hollow extension rising from the closure and communicating with the cup, a perforated mouth 85 piece carried by the extension, and a spring pressed valve arranged within the mouth piece, and controlling the communication between the mouth piece and the cup, and said valve being moved to open position by suction through the mouth piece.

In testimony whereof I affix my signature.

GROVER C. APPLE.
